UNITED STATES PATENT OFFICE.

LEONARD D. CHANDLER, OF NORTH ABINGTON, MASSACHUSETTS.

SIGNAL FOR FIRE-SPRINKLER SYSTEMS.

1,215,909.

Specification of Letters Patent. Patented Feb. 13, 1917.

Application filed March 22, 1911. Serial No. 616,197.

To all whom it may concern:

Be it known that I, LEONARD D. CHANDLER, a citizen of the United States, and a resident of North Abington, in the county of Plymouth, State of Massachusetts, have invented 5 an Improvement in Signals for Fire-Sprinkler Systems, of which the following description, in connection with the accompanying drawings, is a specification, like letters on the drawings representing like parts.

This invention relates to signal devices for fire sprinkler and other systems and among other objects provides a signal which always operates on the discharge of water through 15 the automatic sprinkler valves, but is prevented from operation at other times. The invention comprises an apparatus of the type shown in my Letters Patent No. 989,335, dated April 11, 1911, based on an application 20 filed March 4, 1910, and copending with the present application.

The character of the invention may be best understood by reference to the following description of an illustrative embodiment 25 thereof shown in the accompanying drawings, wherein:

Figure 1 is a view partly in elevation and partly in section, of a sprinkler system equipped with a signal device embodying the 30 invention;

Fig. 2 on an enlarged scale is a vertical section through a water meter motor and instrumentalities for operating the signal;

Fig. 3 is a horizontal section taken on line 35 3—3 of Fig. 2;

Fig. 4 on an enlarged scale is a vertical section of a device shown in Fig. 1; and

Fig. 5 is a section taken on line 5—5 of Fig. 4.

Referring to the drawings, 1 designates a 40 main pipe supplying water to branch pipes distributed throughout the building in which the system is installed, a single branch pipe 3 being shown herein provided with usual automatic sprinkler valves 5.

A check valve 7 interposed in said main pipe 1 is carried by an arm 9 pivoted to the wall of an enlarged chamber 11 and normally held on its seat by a weight 13. Access 45 to the valve within the chamber may be had through a removable head 15.

I will now describe a signal and means for operating the same automatically on a reduction in pressure above the valve 7 caused 55 by the opening of the sprinkler valves 5. To this end there is provided in the main pipe 1

a by-pass pipe 17 having one leg entering said pipe beneath the check valve 7 and another leg entering said pipe above said valve. Interposed in this by-pass is switch operating means, herein comprising a casing 19 containing a water meter motor rotative in opposite directions, such for example, as is used in water meter motors of the disk type. Briefly, this motor comprises a disk 21 60 mounted on a ball 23 rotative in a bearing 25 curved to conform to the contour of said ball, said disk being inclosed within a casing 27 having openings permitting water passing through the by-pass pipe to act on the disk 21 and cause the same to oscillate in the casing 27. The ball is provided with a pin 29 projecting upwardly through an aperture in the crown of the bearing 25, said pin being adapted to engage a crank 31 on a 70 short vertical shaft journaled in a frame 33 depending from the top of the casing 19. The oscillatory movements of the disk 21 will cause the pin 29 to oscillate and transmit rotative movements to said short shaft. 75

A switch operating shaft 35 is journaled in a bearing in the top of the motor casing 19 and in a bearing in a plate 37 of a bonnet 39 mounted on said casing 19. To transmit rotative movements from the water meter 80 motor to the shaft 35 at a considerably reduced speed, a gear train 41 is interposed between the short motor operated shaft rotated by the motor pin 29 and the switch operating shaft 35. The switch illustrated herein as operated by the shaft 35 comprises a cupped wheel 43, (Figs. 2 and 3) having a hub 45 loose on said shaft. This wheel is provided with a switch arm 47 having a knife contact 49 adapted to enter between resilient leaves of a fixed contact 51 mounted in an insulating plug 53 threaded into an aperture in said bonnet 55. 90

The contact 51 is connected by a wire 57 to one of the contacts 59 of an electric bell 100 60, the other contact 59 of said bell being connected by a wire 65 to an instrumentality to be referred to. The latter is connected by a wire 67 to a contact 69 on the bonnet 55.

The rotary movements of the knife contact 49 are limited by a heel 71 on said switch arm 47 adapted to engage one or another of two stop lugs 73 and 75 projecting inwardly from the bonnet 55. Said switch arm is normally held with its heel 105 71 against said stop lug 75 by a spiral spring 77 encircling the switch wheel hub 110

and having its inner end attached to the switch arm carrying wheel hub 45 and its outer end attached to the bonnet 55.

In order that the switch shaft 35 may 5 rotate the switch wheel from its open position in which its heel engages the stop 75, to its closed position as shown in Fig. 3, suitable clutch means may be provided. As shown, this clutch means comprises a hub 10 78 (Fig. 3) fast on said shaft 35 and slotted to receive substantially circular expansion springs 79 adapted by their inherent resilience to press against the inner surface of the wall of the cup 43. Their pressure 15 may be varied by spreaders 81 having ends forked to receive said springs and adjustably connected to the hub 78 by studs 83 and set screws 85 thereon. To vary the pressure of said springs against the inner 20 periphery of the cup 43, the set screws 85 may be adjusted toward or from the hub 78 causing the spreaders to flatten the circular springs 79 more or less and thereby vary their pressure on said contact wheel. 25 The switch shaft 35, through the clutch springs 79, will cause the switch wheel 43 to turn until the switch arm has swung its heel from the stop 75 to the stop 73 thereby closing the switch. If the motor continues 30 to rotate, said spring 79 will slip along the inner wall of said wheel without rotating the latter. The spiral spring 77, when energized by the switch closing rotation of the switch wheel, tends to reversely rotate 35 said wheel to bring the switch arm 47 to its open position.

In accordance with the above-described construction, each time that a measured or predetermined quantity of water flows 40 through the by-pass, the switch arm 47 will rotate around to its position shown in Fig. 3 and if the circuit is otherwise closed will complete the closing of the motor switch of the circuit and cause the bell to ring.

45 In order that a signal for a fire sprinkler system may be valuable, it must operate every time the sprinklers open as in the case of fire, or when bad leaks occur in the system, but at no other time. The pressure 50 in the main supply pipe varies from time to time according to the demands on the supply. One of the objects of the invention is to provide means for preventing the operation of the signal on the surging or 55 rushing of water up into the pipe. To this end means is provided for automatically opening the circuit from the motor operated switch to the bell on the occurrence of any such surging so that the motor operated 60 switch may only be effective to operate the signal on the opening of the automatic sprinkler valves.

To this end, the wire 67 leading from the fixed contact of the motor operated switch 65 is connected to a similar fixed contact 87

(Fig. 5) mounted in an insulation plug 89 threaded or otherwise secured to a casing 91 supported in any suitable manner. Within this casing is a switch operating wheel 93 having an arm 95 and a knife contact 97, 70 said wheel being loosely mounted on a shaft 99 journaled in said casing. The movements of said arm 95 are limited by the engagement of a heel on said arm with spaced stops 96, 96 on said casing. The 75 contact wheel is cupped to receive a clutch 101 which may be similar to that described in connection with the meter motor, said clutch including a hub 103 fast on the shaft 99. Also fast on said shaft is a pulley 105 80 (Fig. 4) having a hub 107 secured to said shaft by a set screw 109. On said pulley is a round belt or cord 111 having one end secured to a weight 113 (Fig. 5) conveniently guided in an elongated tube 115 85 secured to the base of the casing 91. The opposite end of the cord 111 is secured to a weight 117 somewhat heavier than the weight 113, the weight 117 being adapted to float on a column of mercury in a tube 90 119 having one end secured to the base of the casing 91 and its opposite end extending within and nearly to the bottom of a closed well 120 of greater capacity than said tube 119, so that it may at times readily contain 95 all of the mercury therein. The well 120 is connected at its top by a pipe 121 with a chamber 123 interposed in the by-pass 17, herein at a point between the water meter motor and the by-pass leg connecting with 100 the main pipe 1 above the check valve 7, although the pipe 121 may be entered at any other point in the system above said check valve or beyond the water meter motor if desired. The chamber 123 is 105 provided to prevent pressure changes in the pipe 121 from the velocity of water flowing through the by-pass past said chamber.

To prevent the mercury from being 110 pressed up out of the tube 119, a cap 119^a may be provided in the top of said tube having an aperture 119^b for receiving the weight cord 111. To automatically close 115 said aperture when the weight is near the top of said tube, a cone plug or valve 111^a may be secured to said cord 111 just above said weight and the aperture 119^b may be similarly coned to constitute a valve seat for said valve. Although a switch operating 120 means is shown herein in the form of a mercurial gage, it will be understood that other types of pressure responsive switch operating means might be used.

The weighted check valve tends to create 125 a difference in pressure above and beneath the same and as a result there is a tendency for a flow around through the by-pass to equalize the pressure above and beneath the check valve. The water meter motor is re- 130

sponsive to this differential pressure and is rotated in a direction to close its switch on flow of water in one direction and is rotated to open its switch on flow of water in the opposite direction. The water meter motor, therefore, is a gage responsive to this differential pressure indicating whether the pressure is greater beneath or above the check valve. The mercury column device is sensible to static pressure changes in the system and does not indicate the presence of a difference in pressure above and beneath the check valve and is independent of the water meter motor which, in the selected embodiment of the invention, illustrates the gage or means responsive to pressure differences above and beneath the check valve.

The operation of the above described apparatus is as follows:

In case of fire the automatic sprinkler valves 5 will open and permit water to be delivered from the main pipe through the branch pipe and said valves. The opening of the sprinkler valves will cause a reduction of pressure in the system which will be communicated to the mercurial gage. This reduction of pressure will cause the mercury in the tube 119 to drop and with it the weight 117. As a result through the cord, pulley and clutch, the switch arm 95 will be rotated to close the circuit at the mercurial gage. The difference in pressure above and beneath the weighted check valve 7 created by the opening of the sprinkler valves, will cause the water to flow around through the by-pass pipe 17 causing the water meter motor to rotate. After this motor has made a number of rotations which may be predetermined, if desired, the switch operating shaft 35 will have turned sufficiently to make substantially one complete rotation, and through the clutch mechanism connected thereto will rotate the switch wheel 43 and cause the switch arm 47 to move from its open position around to a position in which the knife contact 49 enters between the leaves of the fixed contact 51 (Fig. 3). The circuit is then closed at both the mercurial gage and the meter motor and as a result the bell will sound and signal the opening of the automatic valves.

The water meter motor is rendered ineffective to operate said signal on the occurrence of pressure variations in the system other than that occasioned by the passage of water through the sprinkler valves as follows: For example, an increase of pressure in the system will be transmitted through the liquid in the pipe 121 to the mercury column in the tube 119, causing the column of mercury to rise and carry with it the weight 117 thereon. The lifting of this weight, through the belt 111, will rotate the pulley 105, and the latter through the clutch springs 101, will rotate the switch wheel 93

moving the arm 95 thereof in a clockwise direction (Fig. 5) until the knife contact 97 is separated from the leaves of the fixed contact 87 thereby breaking the circuit to the bell. The clockwise movement of the arm 95 is limited by the engagement of its heel with the fixed stop in the casing. In case the mercury column continues to rise, the pulley will continue to rotate, but the clutch spring 101 will slip around within the switch 75 operating wheel 93 without causing further rotation thereof:

As soon as this pressure decreases or the sprinkler valves open and thereby reduce the pressure above the check valve, the pressure back of the mercury column will be correspondingly reduced and the column will fall and with it the weight 117; thereby rotating the switch arm 95 in a counterclockwise direction causing the knife contact 97 85 to enter between the leaves of the fixed contact 87 as shown in Fig. 5, and thereby complete the circuit at that point. The closing of the water meter motor operating switch may then be effective to complete the 90 closing of the circuit and sound the alarm.

In case the water should flow from above the check valve 7 through the by-pass to the opposite side of said valve, the meter motor would rotate in a direction opposite to that 95 described and would rotate the switch arm 47 away from the fixed contact 51 and thereby open the circuit.

Thus it will be observed that means is provided to break the circuit and prevent 100 the operation of the signal while the sprinkler valves are closed both on the flowing of water out of the system and on an increase of pressure in the system. Said means will always be effective to close the circuit on the 105 reduction of pressure in the system occasioned by the flow of water out through the automatic sprinkler valves.

To further enable an understanding of the operation of the device a variety of 110 conditions may be considered. Among others, there is a pressure variation in the portion of the system extending from beneath the check valve, around through the by-pass and to the sprinkler valves, caused 115 by variation of pressure in the city main. On a drop of pressure the check valve, being, as normally, tight on its seat, will cause the water to flow from the upper side thereof around through the by-pass to the under 120 side thereof. This will reversely rotate the water motor and automatically open the motor operated switch and break the circuit at this point. This drop will also cause or be accompanied by a decrease in the pressure in the by-pass above the check valve, 125 resulting in the lowering of the mercury column and the closing of the switch operated thereby. As a result the circuit is closed at this point, but the alarm will not 130

sound owing to the fact that it is broken at the water meter motor switch.

The variation in the city supply demand will also cause at times an increase in the pressure in the system. This may not be sufficient to lift the check valve from its seat, but may create an impulse or flow tendency up through the by-pass, which might be sufficient to rotate the meter motor enough to close its switch. The alarm is not permitted to sound on the occurrence of such an event since the pressure increase causes the mercury column to rise and operate its switch and automatically break the circuit.

The condition known as "waterhammer" embodies the combination of the rise and fall of pressure just recited, with this difference—that they are pulsations or of short duration; but from the above discussion it will be clear that this will not be effective to sound the signal.

There are apt to be not only pressure changes while the sprinkler valves are closed, but also more or less water motion or flow, caused by the compressing of air pocketed in the system. An inward flow around the by-pass might be sufficient to close the motor operated switch, but the flow into the system while the sprinkler valves are closed increases the pressure, causing the mercury column to rise and open its switch and thereby prevent operation of the signal.

A flow in the opposite direction, or out of the system, reverses the motor and opens its switch, but this is accompanied by a fall in pressure, causing the mercury column to lower and close its switch, and in this case the alarm will not operate.

It will be observed that the flow responsive motor is entirely independent of the pressure responsive mercury column, or in other words, their co-operation resides merely in controlling the circuit, but as mechanisms they are entirely independent, one being responsive or taking care of one condition and the other being responsive or taking care of another condition. They are absolutely independent of one another as far as conditions in the system are concerned.

From the above discussion, it will be apparent that the only condition under which the alarm will sound will be when there is a flow into the system accompanied by a fall in pressure, and clearly this can only occur when the sprinkler valves are open and there is a flow through them.

To recapitulate,—

1. It should be understood that in nearly every system there may be a quantity of air confined, which is elastic and compressible.
2. There are all kinds of pressure variations in the system due to changing conditions of the supply.

3. There are changes in directions and velocities of flow, in the system, made possible by the confined air above referred to, and caused by unbalanced forces or pressures.

4. Now if we throttle, check, or retard the admission of water into the system as we have in this case by a weighted check valve, in the supply pipe we will note different possible conditions as follows:

Pressure.

Condition *a*: Pressure rises in system when pressure of supply to the system rises, from any cause, such for example as water-hammer, or filling of stand pipes.

Condition *b*: Pressure falls in system when pressure of supply to system falls from whatever cause.

Condition *c*: Pressure falls in system when sprinkler valves open, or bad leaks occur in system.

Flow.

Condition *d*: Water flows up into system when pressure of supply rises, from whatever cause.

Condition *e*: Water flows back out of system when city pressure falls, from whatever cause.

Condition *f*: Water flows up into system when sprinklers open or bad leaks occur in system.

5. From the above conditions the following observations may be made:

(1) Any alarm device dependent upon the pressures in the system must be able to distinguish between condition *b* and condition *c*, in order not to give false alarms, as in each case the pressure falls, but in condition *c* the sprinkler opens and we want an alarm and in the case *b* the sprinkler does not open and we do not want an alarm. Condition *b* may be distinguished from condition *c* by a device responsive to the direction of water flow in the supply pipes to the system. In condition *b* water flows down out of the system. In condition *c* water flows up into the system.

Thus we see how a device responsive to the direction of flow in supply pipes will distinguish condition *b* from condition *c*.

(2) Any alarm device dependent upon the direction of flow in the supply pipes to the system must be able to distinguish between condition *d* and condition *f* in order not to give false alarms, as in each case the flow is in the same direction, but in condition *f* the sprinkler opens and we want an alarm, and in the condition *d* the sprinkler does not open and we do not want an alarm.

Condition *d* may be distinguished from condition *f* by a device recording the changes in pressures in the system.

In case *d* the pressure in the system rises.

In case *f* the pressure in the system falls.

Thus we see how a device for recording changes of pressures in the system will distinguish condition *d* from condition *f*.

5 It is evident that if the above referred to pressure responsive device and flow responsive device, each acting independently of each other, are used jointly to control the operation of an alarm the latter will be 20 sounded only when conditions *c* and *f* exist and at no other times.

As shown herein, the signal is operated by an electric circuit with two separate switches in series, one being controlled by the pressure device, and the other being controlled by the flow device, and only when conditions *c* and *f* exist are both switches closed and the circuit completed to sound the signal.

Obviously the switches might be otherwise arranged and other devices might be operated by the pressure and flow responsive devices if desired, without departing from the spirit and scope of the invention.

Having described one embodiment of the invention without limiting myself thereto, what I claim as new and desire to secure by Letters Patent is:

1. An apparatus of the class described, comprising, in combination, a sprinkler system having automatic sprinkler valves therein; a signal; and means for operating the latter on the flow of water out of the system through said valves, said means including a controlling device for preventing operation of the signal when the sprinkler valves are closed on a flow of water away from said valves and another independent controlling device for preventing operation of the signal from increasing pressure in said system.

2. An apparatus of the class described, comprising, in combination, a sprinkler system having automatic sprinkler valves therein; a signal; and means for operating the latter on a flow of water in one direction through the system, said means including a controlling device for preventing operation of the signal on a flow of water in the opposite direction through the system and an other independent controlling device for preventing operation of the signal from increasing pressure in the system.

3. An apparatus of the class described, comprising, in combination, a sprinkler system having automatic sprinkler valves therein; a signal; and means for jointly controlling the latter on the discharge of water through the valves, said means including independently operating flow and pressure responsive means continually in communication with the system and responsive to conditions in the system.

4. An apparatus of the class described, comprising, in combination, a sprinkler system having automatic sprinkler valves there-

in; a signal; and plural means, one continually responsive to pressure in the system and another responsive to flow of water through the system for jointly controlling the operation of the signal.

5. An apparatus of the class described, comprising, in combination, a sprinkler system having automatic sprinkler valves therein; a signal; and means for operating the latter after a predetermined volume of 75 water has been discharged through the valves, said means having provision for preventing operation of the signal from increasing pressure in the system.

6. An apparatus of the class described comprising, in combination, a sprinkler system having automatic sprinkler valves therein; a signal; electrical connections for the latter including an electric circuit; and means for automatically closing said circuit 85 on the discharge of water through the valves including means for preventing operation of the signal on increasing pressure in the system, and on flow of water away from said valves.

7. An apparatus of the class described comprising, in combination, a sprinkler system having automatic sprinkler valves therein; a signal; electrical connections for the latter including a normally open electric circuit; and means for closing said circuit when water flows into the system, said means having provision for breaking the circuit on an increase of pressure in said 95 system or a flow of water back out of said 100 system.

8. An apparatus of the class described comprising, in combination, a sprinkler system having automatic sprinkler valves therein; a signal; electrical connections for the latter including a normally open electric circuit; switches in said circuit; means for automatically closing said switches on the discharge of water through said valves; said means having provision for automatically breaking the circuit on an increase of pressure in said system or a flow of water back out of said system.

9. An apparatus of the class described comprising, in combination, a sprinkler system having automatic sprinkler valves 115 therein; a signal; and automatic means for operating said signal including independently actuated co-operating pressure and flow responsive means continually responsive to conditions in the system.

10. An apparatus of the class described comprising, in combination, a sprinkler system having automatic sprinkler valves 125 therein; a signal; means for jointly controlling said signal and including an electric circuit and switches therein; and pressure responsive means controlling one of said switches and flow responsive means controlling another switch.

11. An apparatus of the class described, comprising, in combination, a sprinkler system including a main supply pipe; a check valve in said pipe; a by-pass around said check valve; a signal; flow responsive means in said by-pass for controlling the operation of said signal; and pressure responsive means coöperating with said flow responsive means, but operating independently of said flow responsive means for controlling the operation of the signal. 65
12. An apparatus of the class described, comprising, in combination, a sprinkler system having automatic sprinkler valves therein; a signal; and means for controlling the latter including flow responsive means and a pressure gage operable independently of one another and continually responsive to conditions in the system. 70
13. An apparatus of the class described, comprising, in combination, a sprinkler system having automatic sprinkler valves therein; a signal; and means for operating the latter including a water meter motor responsive to flow through the system and a pressure gage continually responsive to pressure variations in the system, said motor being operable independently of said gage. 75
14. An apparatus of the class described, comprising, in combination, a sprinkler system having automatic sprinkler valves therein; a signal; and means for operating the latter including a water meter motor and a pressure gage for jointly controlling the operation of said signal, said motor being operable independently of said gage. 80
15. An apparatus of the class described, comprising, in combination, a sprinkler system having automatic sprinkler valves therein; a signal; a main supply pipe in said system; a weighted check valve in said pipe; a by-pass around said check valve; a rotative water motor in said by-pass; and a pressure gage in communication with the system, said motor and gage being adapted to jointly control the operation of said signal. 85
16. An apparatus of the class described comprising, in combination, a sprinkler system having automatic sprinkler valves therein; a signal; and means for controlling the latter including an electric circuit having two switches and a bell therein; a water motor for operating one of said switches and a pressure gage continually in communication with the system for operating the other of said switches. 90
17. An apparatus of the class described comprising, in combination, a main, a check valve therein, a sprinkler system beyond said check valve having automatic sprinkler valves therein; a signal; and means for operating the latter including means responsive to flow into the system and means in- 95
- dependent of said responsive means and responsive to pressure changes on flow into or out of the system. 100
18. An apparatus of the class described comprising, in combination, a sprinkler system including a pipe; automatic sprinkler valves for the latter; a check valve in said pipe; a by-pass around said check valve; a signal; and means for controlling the latter including flow operated means and pressure operated means independent of said flow operated means and responsive to pressure changes on flow into or out of the system, said controlling means being continuously responsive to conditions in the system. 105
19. An apparatus of the class described comprising, in combination, a sprinkler system having automatic sprinkler valves therein; a signal; an electric circuit therefor; and means for operating the signal on the opening of the system including switches in said circuit, one opened by increase of static or other pressure in said system and closed on decrease of pressure in said system and the other closed on flow into the system. 110
20. An apparatus of the class described comprising, in combination, a sprinkler system having automatic sprinkler valves therein; a signal; an electric circuit therefor; means for operating the signal on the opening of the system; a liquid column in communication with the system; a switch in said circuit; and clutch means for transmitting movements of said column to said switch to automatically close the switch on the discharge of water through the sprinkler valves and automatically open the switch on the occurrence of increase of pressure in the system. 115
21. An apparatus of the class described comprising, in combination, a sprinkler system having automatic sprinkler valves therein; a signal; and means continually responsive to changes in the system for jointly controlling said signal and including an electric circuit; switches in said circuit; means for closing said switches on the discharge of water through said valves; and means tending to open said switches. 120
22. An apparatus of the class described comprising, in combination, a sprinkler system having automatic sprinkler valves therein; a signal; an electric circuit therefor; a switch in said circuit; a wheel carrying said switch; a water meter motor interposed in the system for rotating said wheel in one direction to close said switch and operate the signal; and means energized by movements of said switch wheel tending to reversely rotate said wheel. 125
23. An apparatus of the class described comprising, in combination, a sprinkler system having automatic sprinkler valves there-

in; a signal; an electric circuit therefor; a switch in said circuit; a wheel carrying said switch; a water meter motor interposed in said system; a speed reduction gear train 5 interposed between said motor and said switch wheel for transmitting rotative movement from the former to the latter to close the switch and operate the signal; and automatic means tending to reversely rotate said 10 switch wheel.

24. An apparatus of the class described comprising, in combination, a sprinkler system having automatic sprinkler valves therein; a signal; an electric circuit therefor; a 15 switch in said circuit; a water meter motor interposed in said system; and clutch means for transmitting rotative movements from said motor to said switch wheel to close the switch on the passage of water through said 20 valves.

25. An apparatus of the class described comprising, in combination, a sprinkler system having automatic sprinkler valves therein; a signal; and means for operating the 25 latter on the opening of the system including a liquid column container in communication with said system, a weight floating on said column; a pulley, a belt passing from said weight over said pulley for rotating the latter on the variation in the 30 height of said column and means operated by said pulley for preventing the operation of said signal from increased pressure in the system.

35 26. An apparatus of the class described comprising, in combination, a sprinkler system having automatic valves therein; a signal; and means for operating the latter on the opening of the system including a liquid 40 column container in communication with said system, a pulley, a belt passing over said pulley having weights on the ends thereof, one of said weights being carried on said column, and means operated by said 45 pulley for preventing the operation of the signal excepting on a reduction of pressure in the system.

27. An apparatus of the class described comprising, in combination, a sprinkler system 50 including a main pipe and sprinkler valves for discharging water therefrom; a check valve in said main pipe; a by-pass around said check valve communicating with said main pipe on opposite sides of said 55 check valve; a signal; and means for operating the latter comprising a water meter motor in said by-pass; a mercury column container in communication with said by-pass, said column being responsive to pressure variations in the system; and means 60 operated by the rise and fall of said column for preventing the operation of said signal excepting on a reduction of pressure in the system.

28. An apparatus of the class described 65 comprising, in combination, a sprinkler system; a signal; and means for controlling the latter including an electric circuit, switches in said circuit; and means continuously responsive to conditions in the system 70 having provision for operating said switches in a manner similar to one another including flow responsive means coöperating with one of said switches and means independent of said flow-responsive means coöperating with 75 the other switch and responsive to pressure changes on flow into or out of the system.

29. An apparatus of the class described comprising, in combination, a sprinkler system; a signal; and means for controlling the 80 latter including means responsive to pressure changes on flow into or out of the system and flow operated means continually in communication with and responsive to conditions in the system, said flow and pressure 85 responsive means being constructed and arranged to operate the signal only on flow into the system accompanied by a fall in pressure in the system.

30. An apparatus of the class described 90 comprising, in combination, a system, a signal, an electric circuit therefor; switches in said circuit and pressure and flow responsive means having provision automatically operating to close said switches to give said signal 95 only on a flow into the system accompanied by a fall in pressure such flow and fall coöperating to operate the signal.

31. An apparatus of the class described 100 comprising, in combination, a system including means for delivery therefrom, a signal, and means for operating the latter having provision for automatically making the signal only on flow through said delivery means accompanied by a drop in pressure 105 such flow and drop of pressure acting in conjunction to operate the signal.

32. An apparatus of the class described comprising, in combination a fire extinguisher system, a signal, and means for 110 operating the latter having provision for making the signal only on the occurrence of a flow into the system accompanied by a simultaneous fall in pressure said signal being operated by the coöperative action of 115 such flow and fall of pressure simultaneously.

33. In a sprinkler system, the combination of a check valve, a by-pass around said check valve, a gage in said by-pass responsive to pressure differences above and beneath said valve, a pressure gage responsive to static pressures in the system, and a signal controlled by the joint operation of said 120 gages.

34. In an automatic sprinkler system, the combination of a check valve, a by-pass around said check valve, a differential pres- 125

sure gage responsive to pressures above and beneath said check valve, a pressure gage responsive to static pressures in the system and a signal controlled by the conjoint operation of said gages.

35. In combination, a sprinkler system, supply means therefor, means tending to create a differential pressure between the supply and system, means responsive to said differential pressure, means continuously actively responsive to static pressure in the

system independent of said differential pressure creating means and a signal, controlled by and operable only by the joint operation of both of said responsive means.

In testimony whereof, I have signed my name to this specification, in the presence of two subscribing witnesses.

LEONARD D. CHANDLER.
